R. EBERHARDT

GRIPPING LAMP AND FUSE HOLDER

Filed April 26, 1923

Inventor

By *Johann H. Polachek* Attorney

UNITED STATES PATENT OFFICE.

ROBERT EBERHARDT, OF NEW YORK, N. Y.

GRIPPING LAMP AND FUSE HOLDER.

Application filed April 26, 1923. Serial No. 634,785.

To all whom it may concern:

Be it known that I, ROBERT EBERHARDT, a citizen of Hungary, residing at New York, in the county of New York and State of 5 New York, have invented certain new and useful Improvements in Gripping Lamps and Fuse Holders, of which the following is a specification.

This invention relates generally to electric incandescent lamps, having more particular reference to the construction of the screw threaded member in the socket element into which the rear end of the lamp bulb is screwed, the invention being also 10 adapted for use in connection with fuse sockets.

The invention has for an object the provision of an improved means, of simple and inexpensive construction, whereby the bulb 20 may be more quickly attached to the said screw threaded member.

For further comprehension of the invention, and of the objects and advantages thereof, reference will be had to the following description and accompanying drawings, and to the appended claims in which the various novel features of the invention are more particularly set forth.

Fig. 1 of the drawings is a side view of 30 an electric incandescent lamp having the invention applied to its socket member.

Fig. 2 is a partial elevational view at right angles to Fig. 1, the shell being shown in section and the interior parts in elevation.

Fig. 3 is a horizontal sectional view taken on the line 3—3 of Fig. 2.

Fig. 4 is a like view taken on the line 4—4 of Fig. 2.

Fig. 5 is a similar view to Fig. 4 but showing a somewhat modified construction. Fig. 6 is a fragmentary elevation showing a means for locking the lamp in place.

In the drawings the reference number 10 indicates the shell of the socket member of the lamp, the usual bulb being indicated at 11 and the switch button at 12. The shell 10 is provided with the usual insulating lining 13. According to this invention the 15 sleeve which grips the bulb end is of expandible construction, whereby the bulb can be more readily attached or removed.

As here shown this sleeve is divided diametrically into two halves or sections 15 and 16 respectively, which are formed with screw threads complementary to one another,

these sections being formed with inturned flanges 15' and 16' at their lower edges and are formed with hinge ears 18 and 19 adjacent their inner ends which surround a hinge pindle 20 extending longitudinally in the socket adjacent one side thereof, and which is supported by the usual porcelain block 21 which carries the switch mechanism. The hinge ears 18 freely surround the pindle 60 20, while the ears 19 are fixed thereto. One of the ears 18 has an integral extension 18' to which is fixed a lateral arm 23, while the pindle 20 has fixed thereto another lateral arm 24. 65

These arms project from the side of the socket, generally toward the centre thereof, and their free ends are positioned on opposite sides of an oval disk 26 which is rotatably supported in the socket, being fixed on 70 a stud 27 which extends in the median line of the socket and which projects from the porcelain block 21. This disk 26 forms a cam by whose partial rotation the arms 23, 24 are moved to open the two parts 15 and 16. To rotate this cam it has fixed co-axially thereto a gear 29 engaged on opposite sides by a pair of rack bars 30 slidabie in suitable 75 guide members 31 in the shell 10 and each projecting at one end through the latter and having a push button 30' on its outer end. These rack bars have connected thereto the tension springs 32 whereby they are returned to normal position.

Surrounding the extended lower end of 90 the hinge pindle 20 is a coiled spring 34 which both serves to support the members 15, 16 and to urge the same toward one another to grip the bulb end, the spring being connected at opposite ends respectively 95 to the pindle 20 and the member 15, which is freely engaged with said pindle.

As will be apparent, when it is desired to attach a bulb to the socket it is only necessary to press the buttons 30' in unison, 100 which will rotate cam 26 and cause the arms 23, 24 to swing away from one another, and since each arm has a fixed connection with one of the members 15, 16 the latter will be caused to likewise swing away from one another so that the bulb end can be readily inserted. When the buttons are released the spring 34 urges the two members 15, 16 toward one another, causing them to grip 105 and hold the bulb end. For making the 110 electrical connections the upper end of the pindle 20 may be engaged in any suitable

manner with one of the lead wires, while an angular member 36 is extended through the porcelain block 21 to be engaged at one end with the other lead wire and at its opposite end with the usual centre contact on the bulb end. I may also provide a pair of spring fingers 15^a and 16^a which clasp the members 15 and 16 to urge them toward one another.

10 In Fig. 5 I have shown an arrangement in which the two members 15, 16 are formed on one side with crossed fingers 40, 41 which project through suitable slots 42 in the wall of the shell and which are moved toward one another to open the bulb engaging parts; it being understood that the spring 34 urges these parts together as in the other construction.

15 As shown in Fig. 6 I may mount a rotary cam 43 on the shell 10 between the fingers 40 and 41 and which is locked by a suitable key inserted through a key-hole 44 therein to prevent expansion of the bulb holding member, the inturned flanges 15' and 16' 20 then preventing withdrawal of the bulb.

25 Having thus described my invention what I claim as new and desire to protect by Letters Patent of the United States is as follows:

30 1. In an electric socket, a casing, an expansible bulb holding member in said casing, said member being in the form of a sleeve formed in two semi-cylindrical sections, means hinging the said sections within the casing, arms fixed to the respective sections, and a rotary cam member adapted to engage each arm to expand the said bulb holding member.

35 2. In an electric socket, a casing, an expansible bulb holding member in said casing, said member being in the form of a sleeve formed in two semi-cylindrical sections, means hinging the said sections within the casing, arms fixed to the respective sections, 40 and a rotary cam member adapted to engage each arm to expand the said bulb holding member, and gear and rack means for rotating said cam.

45 3. In an electric socket, an expansible bulb holding member in the form of a sleeve formed in two semi-cylindrical sections, hinge ears on the respective sections, a hinge pintle freely engaged with the ears on one section and fixed to the ears on the other section, a pair of arms projecting respectively from the hinged pintle and the first 50 named ears, and a cam for operating said arms to open the said bulb holding member.

55 4. In an electric socket, an expansible bulb holding member in the form of a sleeve

formed in two semi-cylindrical sections, hinge ears on the respective sections, a hinge pintle freely engaged with the ears on one section and fixed to the ears on the other section, a pair of arms projecting respectively from the hinged pintle and the first named ears, and a cam for operating said arms to open the said bulb holding member, 60 said cam being in the form of an oval disk adapted for partial rotation.

5. In an electric socket, an expansible bulb holding member in the form of a sleeve formed in two semi-cylindrical sections, hinge ears on the respective sections, a hinge pintle freely engaged with the ears on one 65 section and fixed to the ears on the other section, a pair of arms projecting respectively from the hinged pintle and the first named ears, and a cam for operating said arms to open the said bulb holding member, 70 said cam being in the form of an oval disk adapted for partial rotation, a gear fixed co-axially to said disk and manually operable rack bars engaging said gear to rotate the latter in one direction.

6. In an electric socket, an expansible bulb holding member in the form of a sleeve formed in two semi-cylindrical sections, hinge ears on the respective sections, a hinge pintle freely engaged with the ears on one 75 section and fixed to the ears on the other section, a pair of arms projecting respectively from the hinged pintle and the first named ears, and a cam for operating said arms to open the said bulb holding member, 80 said cam being in the form of an oval disk adapted for partial rotation, a gear fixed co-axially to said disk and manually operable rack bars engaging said gear to rotate the latter in one direction.

85 7. In an electric socket, an expansible bulb holding member in the form of a sleeve 90 formed in two semi-cylindrical sections, hinge ears on the respective sections, a hinge pintle freely engaged with the ears on one section and fixed to the ears on the other section, a pair of arms projecting respectively from the hinged pintle and the first named ears, and a cam for operating said arms to open the said bulb holding member, 95 said cam being in the form of an oval disk adapted for partial rotation, a gear fixed co-axially to said disk and manually operable rack bars engaging said gear to rotate the latter in one direction, and 100 springs connected to said rack bars whereby the latter are moved in an opposite direction.

105 8. In an electric socket, an expansible bulb holding member in the form of a sleeve 110 formed in two semi-cylindrical sections, hinge ears on the respective sections, a hinge pintle freely engaged with the ears on one section and fixed to the ears on the other section, a pair of arms projecting respectively from the hinged pintle and the first named ears, and a cam for operating said arms to open the said bulb holding member, 115 and a spring engaged at one end with said pintle and at its other end with one of the first named ears and acting to contract said bulb holding member.

In testimony whereof I have affixed my signature.

ROBERT EBERHARDT.
